UNITED STATES PATENT OFFICE.

EDWARD E. KRETZSCHMAR, OF NEW ULM, TEXAS.

DESIGN FOR A TINNER'S HAMMER.

46,882.

Specification for Design.

Patented Jan. 26, 1915.

Application filed September 28, 1914. Serial No. 863,995. Term of patent 3½ years.

To all whom it may concern:

Be it known that I, EDWARD E. KRETZSCHMAR, a citizen of the United States, residing at New Ulm, in the county of Austin and State of Texas, have invented a new, original, and ornamental Design for Tinner's Hammers, of which the following is a specification, reference being had to the accompanying drawing, forming part thereof.

The figure is a perspective view, showing my new design.

I claim:

The ornamental design for a tinner's hammer, as shown.

EDWARD E. KRETZSCHMAR.

Witnesses:

ROBERT VOIGT,

BEN E. PESCHEL.
